PULL TOY

William R. McLain, Nashville, Tenn., assignor to Kusan
Incorporated, Nashville, Tenn.

Filed June 29, 1961, Ser. No. 65,755

Term of patent 7 years

(Cl. D34—15)

I claim:

The ornamental design for a pull toy, as shown.
